U.S. Cl. 260—613 4 Claims

ABSTRACT OF THE DISCLOSURE

This invention relates to compounds exhibiting marked choleric activity. These compounds of the invention are phenyl-alkyl carbinols and phenyl-cycloalkyl carbinols whose aromatic rings are substituted by at least one hydroxyl and/or alkoxy group.

The main purpose of this invention consists in the provision of a novel series of compounds of the above type, having a marked choleric activity.

The invention covers also a method for producing said compounds. The compounds according to the invention may be expressed by the following formula:

(Formula I) 30

wherein when R' is $-C_4H_9n$, then

TABLE

Compound	Dose, mg./kg. per os	Increments in respect of initial value (ml.) after the—					Σ increment in respect of control	
		1st hr.	2nd hr.	3rd hr.	4th hr.	5th hr.	1-2 hrs.	Total
Controls (blank)		-.04	-.02	-.11	-0.10	-.13	-----	0
3,5-dimethoxy-4-hydroxyphenyl-n-butyl-carbinol	50	+.28	+.12	-.04	-.08	-.13	.46	.58
3-ethoxy-4-hydroxyphenyl-n-butyl-carbinol	50	+.36	+.17	0	-.07	-.07	.59	.79
3-hydroxy-4-methoxyphenyl-carbinol	50	+.23	+.07	-.03	-.06	-.11	.36	.50
3-methoxy-4-hydroxyphenyl-cyclohexyl-carbinol	50	+.24	+.24	+.24	0	-.07	.54	1.05
4-hydroxyphenyl-n-butyl-carbinol	50	+.40	+.28	+.07	-.09	.02	.74	1.15
3,4-dihydroxyphenyl-n-butyl-carbinol	50	+.23	+.03	+.03	-.09	.12	.29	.42
CONVENTIONAL DRUGS								
Cholipin-1-phenyl-pentanol-verecolen	50	+.22	+.07	-.06	-.10	-.18	.35	.40
(1-hydroxy-4-phenyl-cyclohexyl)-butyric acid	50	+.11	+.18	+.08	+.01	-.05	.35	.75
Phenylamyl Flubilar-sodium camphorate	50	+.22	+.14	+.01	-.06	-.11	.42	.58
Oragallin-diethylamide of the 3-chloro-pyridazil-6-mercaptopo-acetic acid	50	+.14	+.02	-.05	0	-.14	.22	.38

and when R' is

then

The main feature of compounds according to the invention consists in that the biological activity is strictly dependent on the presence of the substituent $-\text{OH}$ in the

2

benzene ring. The compounds according to the invention show a high choleric activity, which is unusually marked within the first two hours after the administration of the drug, while an appreciable attenuation of said activity is noticed in the following hours.

Such course of the activity during the course of time, is of fundamental importance, since it is preferable that the choleric action be exerted in the course of digestion, and not beyond it; thus, the drug will simulate the physiological behaviour.

Owing to the above-mentioned properties, the compounds according to the invention may be viewed as drugs useful in the therapy of intestinal dysfunctions originating from slight or middle hepatic insufficiencies.

15 The choleric activity of the products of the invention has been ascertained by means of pharmacological tests conducted on rats and dogs by the method of extemporary biliary fistula, the drugs having been administered by oesophageal and intestinal scoop. The minimal doses, ascertained as efficacious for the above-stated two animal

The acute toxicity of the compounds in question, as tested on rats for the different administration routes, is significantly low, since doses 20-40 times greater than the efficacious one are needed to cause the death of 50% of animals to which the drug was given by mouth, while the subacute toxicity tests, continued through a time of 3 weeks, and with doses 5-6 times greater than the effective dose, did not result in any detrimental effect.

30 A confirmation of the expected pharmacologic-therapeutic properties has been found by clinical experimentation, since the compounds according to the invention have permitted the obtention of significant beneficial effects in the treatment of morbid conditions of liver and hepatic
35 ducts.

In order to demonstrate the effective pharmacologic activity of the compounds according to the invention, when compared with the traditional and conventional drugs, the absolute values of increments in the biliary secretion, in respect of controls—and above all in the first two hours after the administration of drugs, are tabulated below:

60 The compounds in question were obtained by causing a substituted aromatic aldehyde to react with the suitable alkylmagnesium halogenide in ether or tetrahydrofuran, whereupon the resulting complex compound is decomposed by means of diluted, aqueous mineral acids, or by 65 a solution of ammonium chloride, the reaction solvent is evaporated, and aryl-alkyl carbinol is isolated by crystallization or distillation.

70 A particular feature of this invention consists in that the aryl-alkyl carbinols having phenolic —OH can be obtained, by the above-described method, starting from the

corresponding aldehydes, which phenolic groups are either free, or esterified, as shown in the diagram below:

The following, non restrictive examples, are only intended to provide for a better understanding of the invention.

3-ethoxy 4-hydroxy-phenyl-butyl-carbinol

Formula I, wherein

and wherein R' is $-C_4H_9n$.

38 g. (1.56 mole) of Mg and one iodine crystal were put into a three-liters, round-bottomed, four-necked flask, fitted with a reflux condenser having a $CaCl_2$ stopper, sealed stirrer, dropping funnel and pipe for inert gas; then, while stirring, 80 ml. of an ether solution containing 86 ml of n-butyl-bromide were added in two or three portions, allowing the same time a flow of dry N_2 to pass through with water, and additional ether solution of n-butyl bromide was added at a rate such as to keep the ether at its boiling point, until attaining a total addition of 213.6 g. (1.56 mole) of butyl bromide, in 300 ml. of ether. After the end of such addition, the stirring was continued for one hour more, then, a solution of 44 g. of ethyl-vanillin in 880 ml. of ether was added dropwise through the funnel, in a time of 90 min., again while stirring and under an atmosphere of dry nitrogen.

After the end of the ethyl-vanillin addition, the stirring was continued for one hour more, whereupon the reaction mixture was slowly poured on 3 kg. of crushed ice, and finally acidified with diluted H_2SO_4 , using Congo red as indicator.

The supernatant ether layer was decanted, and the aqueous layer was repeatedly extracted with ether; the ether extracts were put together, washed with an aqueous solution of bicarbonate, dried on Na_2SO_4 and evaporated. The solid residue thus obtained was recrystallized from a little benzene: M.P. 75° C. (Kofler).

Formula I, wherein:

3-hydroxy-4-methoxy-phenyl-carbinol

R' is C_4H_9n .

80.16 g. (0.585 mole) of n-butyl-bromide dissolved in 300 ml. of ether were added to 14.2 g. (0.585 mole) of Mg. in the same manner as stated in the preceding example, and then a solution of 25.6 g. (.1 mole) of 3-benzyloxy-4-methoxy-benzaldehyde in 400 ml. of ether was added in the reaction flask, again by the same procedure. The reaction mixture was finally slowly poured on ab. 1 kg. of ice-water and then acidified with diluted H_2SO_4 .

The supernatant ether layer was decanted, the aqueous layer was repeatedly extracted with ether, the ether extracts were put together, and repeatedly shaken with a 5% solution of $NaOH$; the alkaline solutions were put together and saturated with CO_2 , and the supernatant oily layer was extracted with ether; the oily residue left by the washed dehydrated and evaporated ether extract, was crystallized from petroleum ether, and after the subsequent

purification by crystallization from benzene and petroleum ether, gave colorless crystals M.P. 44° C. (Kofler).

By the above described general methods, and following the procedures as stated in the foregoing examples, the following products have been obtained;

(1) 3,5-dimethoxy-4-hydroxyphenyl-n-butyl-carbinol

Formula I, wherein:

and R' is $-C_4H_9n$.

crystals, M.P. 102° C.

(2) 3,4-dihydroxyphenyl-n-butyl-carbinol

Formula I, wherein:

and R' is $-C_4H_9n$.

Crystals: M.P. 125° C.

(3) 3-methoxy-4-hydroxyphenyl-cyclohexyl-carbinol

Formula I, wherein:

and R' is

Crystals: M.P. 139° C.

(4) 4-hydroxyphenyl-n-butyl-carbinol

Formula I, wherein:

and wherein R' is C_4H_9n .

Colorless crystals, M.P. 76-7° C.

What we claim is:

1. A compound selected from the group consisting of 3,5-dimethoxy-4-hydroxyphenyl-n-butyl-carbinol; 3-ethoxy-4-hydroxyphenyl-n-butyl-carbinol; 3-hydroxy-4-methoxy-phenyl-carbinol; 3-methoxy-4-hydroxyphenyl-cyclohexyl-carbinol; 4-hydroxyphenyl-n-butyl-carbinol; and 3,4-dihydroxyphenyl-n-butyl-carbinol.
2. 3,5-dimethoxy-4-hydroxyphenyl-n-butyl-carbinol.
3. 3-methoxy-4-hydroxyphenyl-cyclohexyl-carbinol.
4. 3,4-dihydroxyphenyl-n-butyl-carbinol.
